(57) **CLAIM**

The ornamental design for a safe, as shown and described.

DESCRIPTION

FIG. 1 is a front perspective view of a safe showing our new design;

FIG. 2 is a top view thereof;

FIG. 3 is a front view thereof;

FIG. 4 is a bottom view thereof;

FIG. 5 is a right side view thereof;

FIG. 6 is a rear view thereof;

FIG. 7 is a left side view thereof;

FIG. 8 is an enlarged front elevation view of the handle of the safe, shown separately for ease of illustration;

FIG. 9 is an enlarged side elevation view of the handle of the safe, shown separately for ease of illustration;

FIG. 10 is a front perspective view of the handle of the safe, shown separately for ease of illustration;

FIG. 11 is an enlarged top plan view of the handle plate of the safe, shown separately for ease of illustration;

FIG. 12 is an enlarged left side elevation view of the handle plate of the safe, shown separately for ease of illustration;

FIG. 13 is an enlarged front elevation view of the handle plate of the safe, shown separately for ease of illustration;

FIG. 14 is an enlarged right side elevation view of the handle plate of the safe, shown separately for ease of illustration;

FIG. 15 is an enlarged bottom plan view of the handle plate for the safe, shown separately for ease of illustration; and,

FIG. 16 is a front perspective view of the handle plate of the safe, shown separately for ease of illustration.

The broken lines form no part of the claimed design.

1 Claim, 5 Drawing Sheets
